ABSTRACT: A hoist "payout" and "retrieval" control lever having two separate and oppositely disposed control arms on the hoist's normally neutrally constrained control rod. Actuation of one or the other arms, respectively, pays out or retrieves the cable. Also, movement of one arm causes it to engage and move the other arm, except that there is therebetween a built-in disengaging feature to insure that excessive retrieving motion will not trigger the payout motion.

CONTROL LEVER FOR HOISTS

This application is a continuation of application Ser. No. 715,842 filed Mar. 25, 1968, now abandoned.

This invention pertains to a control lever for a hoist, winch, or such similar device, and in particular to a control lever operative for effecting payout and retrieval of the hoist cable.

In the prior art it is common for a hoist to have a control rod, for operating the hoist, which is normally constrained in a neutral position and rotatable in opposite directions to payout and to retrieve the cable, respectively. It is the practice in the prior art to have a single unitized control lever fixed to the control rod for operation thereof. Such control levers have a pair of arms extending in opposite directions from the rod, and each end the arms suspends a rope therefrom for the manipulation of the lever by an operator.

In order to operate the hoist the operator puts tension on the one rope which is attached to the "lowering" arm. This rotates the control rod and lowers the cable so that a work load might be fixed to the hook block. Then the operator applies a tension to the other rope attached to the "raising" arm, which in turn causes the hoist to elevate the load. If because of continued tension on the raising arm rope, the work load is raised excessively, the hook block carried at the cable termination will engage the raising arm and cause it to rise (with the block) and move to the halt position. However, if the hook block is rising at an excessive rate, it will carry the arm up against the hoist housing possibly fracturing the same or otherwise inflicting damage thereto. Additionally, with excessive momentum of the hook block, the raising arm is carried through the stop position and into the alternate lowering position. Accordingly, this causes the hook block again to lower. In an effort to correct the situation, the unintentional lowering of the block, the operator will again briefly, apply tension to the raising arm or rope again to elevate the hook block and to move the raising arm again to the desired stop position. Unless the operator releases the rope in timely fashion, however, the hook block will again cause the arm to strike the hoist housing. Therefore, there will occur a series of repetitive, violent impacts of the raising arm against the hoist housing, which will likely damage the hoist housing, strain the cable, or shear the control rod, unless the operator can quickly command the rapidly occurring reactions.

It is an object of this invention to teach a control lever structure for mounting on a control rod, which rod is rotatable to payout and retrieve cable, with means cooperative with a normal, neutral constraint of the rod for interrupting rod rotation, whereby it is provided for the rod automatically to dwell in a stop position regardless of motion of the control lever mounted thereon.

A feature of this invention comprises having a control lever with two, separate, oppositely disposed control arms carried on the hoist control rod, said rods having surfaces for mutual engagement therebetween except for a built-in disengagement feature which allows for a dwell of the control rod even though said control lever manifests continuing motion.

Further objects and features of this invention will become more apparent by reference to the following discussion taken in conjunction with the accompanying FIG., the same being a side elevation of the novel control lever, in conjunction with a hoist, in which a portion of the hoist housing is broken away to show the arm mounting details and a portion of one arm is broken away to show splining between one arm and the control rod.

As shown in the FIG. a hoist 10 is contained within a hoist housing 12. A lower portion of the housing has been broken away to show the mounting of the novel control lever 14 on the control rod 16.

In accord with practices in the prior art, control rod 16 is normally constrained (by means not shown) in a neutral position, said neutral or at rest position being the "halt" position. When rod 16 is rotated in either of the two directions therefrom, the hoist motor is energized causing the cable to be payed out or retrieved, respectively.

According to the invention, control lever 14 comprises one arm 18 disposed for effecting payout of the cable, said arm and said control rod 16 having splining 20 therebetween which fixes arm 18 on control rod 16. Accordingly, when arm 18 is moved in a rotary direction about the axis of rod 16, rod 16 must necessarily follow the motions therewith. Splining, of course, is but one way of fixing arm 18 relative to rod 16. Other ways, such as keying, and the like, will occur to those knowledgeable in the art. Such other methods are within the spirit of my invention, it being my teaching to have but one of the arms locked to the rod to cause positive, simultaneous rotation of said rod with rotary motion of said one arm.

Control lever 14 comprises another separate arm 22 disposed on control rod 16 for effecting retrieval of the cable.

Arm 22 is freely pivoted on rod 16; rotary motion of arm 22 about the axis of rod 16 does not directly impart motion to rod 16. Cable 24 is shown depending from the hoist 10 and terminates in a hook block 26. Hook block 26 is suspended below arm 22 with cable 24 immediately adjacent said arm 22.

In positions shown in full line illustration for arms 18 and 22, said arms, the hoist motor, and the control rod 16 are all in the halt position. The dashed line positions 28 and 30 represent the dispositions which arm 22 assumes in the payout and retrieval operations, respectively. Dashed line positions 32 and 34, conversely, represent the retrieval and payout positions of arm 18. Control ropes 36 are attached to each of the arms 18 and 22 for enabling remote actuation thereof by the operator.

Finally it is to be noted that arm 22, which is substantially right-angular, has formed thereon, approximately at the "knee" of the angle, a first tang 38. Tang 38 extends perpendicularly therefrom and parallels the axis of rod 16. Arm 22 also has a second tang 40 disposed at a right angle to the first tang, said second tang 40 also extending perpendicularly from arm 22 and parallel to the rod axis. First tang 38 has surface 42 disposed for engaging a surface 44 presented by a lateral edge of arm 18. Said second tang 40 has an engaging surface 46 disposed for operation against a surface 48, a complementary lateral edge of arm 18. An end surface 50 the length of which exceeds the width of arm 18, defines a given distance which separates engaging surfaces 42 and surfaces 46. The purpose of this given distance is noted in the following discussion.

Arms 18 and 22 are in juxtaposition on rod 16, thus, tangs 38 and 40 are positioned astride arm 18. The effect of this structuring is to cause rotary actuation of arm 18 in response to rotary motions of arm 22 about the axis of rod 16. So also, first tang 38 is provided to cause rotary actuation of arm 22 in response to rotary motion of arm 18. The distance along end surface 50, between engaging surfaces 42 and 46, as was noted earlier, is greater than the width of arm 18. As will be pointed out subsequently, the excess distance is provided to facilitate a lull or interruption in the transmission of motion from one arm to the other so that control rod 16 can locate at, and maintain, the halt position.

In operation, when the hoist operator pulls on rope 36 of arm 18, surfaces 42 and 44 engage and cause rotary motion of arm 22 in response to the rotary motion of arm 18. Arm 18 is carried to its payout position 34. Because of the splining 20, control rod 16 is rotated in a first direction causing pay out of cable 24. It will be noted that, as a result of the engagement of surfaces 42 and 44, arm 22 is also carried to its payout position 28.

When the hoist operator pulls down on rope 36 of arm 22 to retrieve cable 24, engaging surfaces 42 of first tang 38, which is in contact with engaging surface 44 of arm 18, swings arm 18 to its retrieve position 32 as arm 22 moves to its retrieve position 30. Arm 18 is locked to the control shaft 16, by virtue of the splining 20, and turns shaft 16 to retrieve the cable. The hoist hook block 26 is raised, as cable is retrieved, until it makes contact with retrieve arm 22. The hoist motor overcomes the pull or hand tension of the operator, and forces the arm 22, which is free to slue about the control rod 16, into the stop position. (As noted earlier, the stop position is that

disposition of arm 22 as represented in the FIG. in solid line illustration.) As arm 22 is being moved to the stop position, tang 38 proceeds to withdraw from, bearing with less force against, payout arm 18 and allows arm 18 to settle in its own stop position. Thus, the hoist brake motor is deenergized.

Any minimal overtravel of the hook block 26, caused by its velocity, or whatever, is without effect on the control rod 16. This is because arm 22 will but pivot through that portion of its rotary motion, relative rod 16, wherein engaging surfaces 42 and 44, and 46 and 48, are removing from and closing on each other, respectively. The length of surface 50 which exceeds the width of arm 18 defines the measure of free pivoting, disengaged from arm 18, which arm 22 will manifest.

In the event an excessive overtravel of the hook block 26 does occur, in which arm 22 is raised until it reaches its payout position 28, then tang 40 contacts arm 18. Surfaces 46 and 48 engage and force arm 18 into its payout position 34. This, in turn, activates the control rod 16 and lowers the hook block 26. As the hook block lowers, it allows the freely pivotable arm 22 to follow therebehind. Subsequently, arm 22 pivots far enough from payout position 28 to separate surfaces 46 and 48 while not yet joining surfaces 42 and 44. Lever 18 settles in the stop position, and all motion is stopped.

The embodiment of my invention disclosed herein teaches the application thereof in association with a hoist. Self-evidently, though, my invention is equally useful with other cable payout and retrieval devices, such as winches, Capstans, and the like.

I claim:

1. In combination with a hoist, having a control rod normally constrained in a neutral position and rotatable in opposite directions therefrom to effect cable retrieval and payout, a control lever, comprising:
control arms drivingly coupled to said rod for executing rotary motions relative the axis of said rod to rotate said rod to cause positive, simultaneous rotation of said rod in response to said rotary motions;
only one of said arms being locked to said rod to cause positive, simultaneous rotation of said rod in response to said rotary motions;
means carried by at least one of said control arms for caus-

5

ing rotary motion of any one of said arms, in both of said opposite directions through rotary motion of another of said arms;

wherein said motion inducing means cooperate with the normal constraint of said rod automatically to provide for a lapse in the inducement of motion in said another arm during the swing of said any one of said arms through a given portion of an arc described by said rotary motions; and:

said motion inducing means comprising means disposed on said one control arm effective for engaging said another arm to cause movement thereof only during the swing of said one arm through portions of said arc other than said given portion.

2. The invention, according to claim 1, wherein said another arm is pivotably coupled to said rod providing for relative rotation therebetween.

3. The invention according to claim 1, wherein said engaging means comprise means effective for causing rotation of said rod immediately coincident with motion of said another arm in one rotary direction and rotation thereof, after a delay, by motion of said another arm in the opposite rotary direction.

4. The invention, according to claim 1, wherein:
two of said arms are arranged on said rod in juxtaposition, one end of each arm coupled to said rod and the other ends thereof extending perpendicularly from said rod in substantially opposite directions; and
said motion inducing means comprising at least one of said two arms having surfaces for effecting a mutual engagement of said two arms to cause a rotary motion of any one thereof to rotate the other.

5. The invention, according to claim 4, wherein:
said engaging surfaces comprise two pairs of surfaces, each of said two arms having a pair, and
one pair being astride the other pair there being given distance between surfaces of said other pair and a greater distance between surfaces of said one pair, so that rotation of said another arm by said one arm is effected only during the swing of said arms through given end portions of an arc described by said rotary motions.
